UNITED STATES PATENT OFFICE.

RICHARD J. GEAR, OF ROXBURY, MASSACHUSETTS.

GARMENT-SUPPORTER.

1,263,225.

Specification of Letters Patent. Patented Apr. 16, 1918.

Application filed January 22, 1916. Serial No. 73,656.

To all whom it may concern:

Be it known that I, RICHARD J. GEAR, a citizen of the United States, residing at Roxbury, in the county of Suffolk and State 5 of Massachusetts, have invented new and useful Improvements in Garment-Supporters, of which the following is a specification.

This invention relates to improvements in garment supporters and more particularly 10 to belts therefor.

The primary object of the invention is the provision of a device of the above stated character, wherein means are employed for detachably connecting the belt to the waist 15 line of a body garment for rendering the same partially invisible.

A further object of the invention is the provision of a device of the above stated character embodying a back strap and an 20 auxiliary supporter having connection with the back strap for supporting the trousers solely from the hips when it is not desirable to tighten such belt around the waist line of the wearer, and relieving the strain usu- 25 ally caused by the belt from the abdomen usually caused by hip supporting garments.

With the above and other objects in view, the invention consists in the novel features, details of construction and combination of 30 parts which will hereinafter be more fully set forth, illustrated in the accompanying drawing and pointed out in the claims appended thereto.

Figure 1 is a view showing the application 35 of my improved belt;

Fig. 2 is a plan view of the belt detached from the garment and illustrated in extended position;

Fig. 3 is a detail view of one of the belt 40 supporting members; and

Fig. 4 is a detail view showing a slight modification of the manner of connecting the belt around the waist line of the wearer in order that the belt will be solely invisible.

Referring more specifically to the drawing, in which like characters of reference 45 denote corresponding parts in the several views; 5 denotes my improved belt consisting of a broadened elastic back strap 6 having attached to the opposite terminals thereof leather tabs 7. Slidably mounted upon the broadened elastic back strap 6 are belt slides 8 which are constructed from a single blank of sheet metal provided with parallel 50 slots 9 presenting outer bars 10 and an intermediate bar 11. The upper end of these

belt slides has formed contiguous therewith an eyelet 12 constituting a rigid limb 13 and a pivoted limb 14 and the object of this eyelet is to engage with the buttons arranged 60 on the inner face of the garment and in this particular instance the eyelets 12 are engaged with the rear buttons 15 of the trousers 16. In the application of this eyelet with the rear buttons 15 it is obvious that the pivoted limb 14 is moved in an outward direction until the eyelet is positioned around the buttons 15, after which the said limb is swung upwardly and thereby preventing the downward movement of the back strap 70 with respect to the trousers and permanently supporting the same in embracing relation with respect to the inner portion of the waist line of the trousers 16. The tabs 7 are formed with upper branch portions 17 and lower 75 branch portions 18, the upper branch portions 17 of the tab has stitched thereto or connected therewith in any preferred manner upper elastic web portions 19 in the form of a looped strap and adjustable through the 80 medium of a buckle 20, that is to say, due to the buckle 20 the web portions 19 may be adjusted to various lengths in order to meet the dimensions required to properly fit around the waist line of the wearer. The 85 free ends of these web portions 19 carry loops 21 which connect with such web portions belt fastening straps 22. Thus far it will be seen that through the medium of the back strap 6, web portions 19 and the belt 90 connecting straps 22, form a complete belt connecting straps 22, form a complete belt to encircle the waist line of the wearer and it is to be understood that due to the particular type of belt fastening straps the belt may be properly adjusted around the waist 95 as is common to trousers supporting belts. Slidably and adjustably mounted upon these web portions 19 is a second set of belt slides 23 which are identical in construction with the belt slides 8 and are applied in the identical manner as described for the application of the belt slides 8 to the buttons 15 and the only difference existing is that the latter referred to belt slides, namely belt slides 23, are adapted to engage with the front buttons 100 24 and, of course, as is apparent from the drawing, these slides are smaller in size than the slides 8. These belt connecting straps 22, however, are adapted to extend through slits 25 formed in the front portion of the 105 trousers in order to give the trousers the appearance of a belt supporting means. In

order not to compel the wearer of the garment to have this encircling belt sufficiently tightened to prevent the sagging or bagging of the trousers, I have provided what might 5 be termed as an auxiliary belt 26 comprising in addition to the back strap 6, lower elastic web portions 27, such portions having connection with the lower branches 18 of the tabs 7 by stitching or otherwise connecting the same thereto and disposing the lower web portions at an angle with respect to the upper web portions 19. The lower web portions 27 in serving as an auxiliary belt are adapted to engage over the hips of the 10 wearer and fasten at the pit of the abdomen through the medium of the fasteners 28 and in order to prevent the auxiliary belt from having a tendency to ride upwardly upon the hips of the wearer, I pass the same 15 through loops 29 preferably attached to the inner face of the trousers pockets 30. The lower elastic web portions 27 constituting the auxiliary belt are adjustable through the medium of the buckles 31. It may be found 20 desirable in the use of a garment supporter of the above stated character to conceal the belt entirely from view, and to this end instead of employing the belt fasteners 22, I remove such fasteners from the loops 21 25 and substitute the type of fastener 32 as illustrated in Fig. 4 of the drawing, and it is to be understood that the slot 33 of this fastener engages with the usual button at the adjacent portion of the front of the 30 trousers.

From the foregoing description, taken in connection with the accompanying drawing, the advantages of construction and of the method of operation will be readily apparent to those skilled in the art to which the 40 invention relates, and while I have described the principles of operation of the device together with the device which I now consider to be the best embodiment thereof, I desire 45 to have it understood that the device shown

is merely illustrative and that such alterations may be made when desired as are within the scope of the claims appended thereto.

I claim:

1. A garment supporting belt comprising 50 a broadened back strap, tabs connected with the opposite ends of said back straps, each tab being provided with upper and lower branch portions, a web portion connected with the upper branch portion of each tab 55 and forming a continuation of the back strap to provide a waist encircling belt, adjustable elastic straps connected with the lowermost branch portions and disposed at an angle with respect to the said web portions and retained against upward movement by the engagement of the same with portions of the garment, and a fastening device for connecting the free ends of the elastic straps at a point at the pit of the abdomen, substantially as and for the purpose set forth.

2. In a garment supporter of the character set forth, the combination with side pockets of the garment having loops, of a 70 belt having connection with the inner waist line portion of the garment, said belt comprising a back strap, a waist encircling belt connected with the opposite ends of said strap, an angularly arranged auxiliary belt 75 connected to the back strap at a point directly below the point of connection of the first mentioned belt and adapted to pass through the loops of the pockets for preventing any upward movement of said auxiliary belt, and means for fastening the free ends of the auxiliary belt at a point at the pit of the abdomen.

In testimony whereof I affix my signature in presence of two witnesses.

RICHARD J. GEAR.
